TRICYCLE

Guy F. Campbell, Hammond, Ind., assignor, by mesne assignments, to American Machine & Foundry Company, New York, N.Y., a corporation of New Jersey

Filed Sept. 24, 1954, Ser. No. 32,426

Term of patent 14 years

(Cl. D34—15)

The single figure is a perspective view of a tricycle, showing my new design.

My design comprises a tricycle having tractor type treads on the tires of the wheels and a hoisting boom extending upwardly and rearwardly from the lower end of the cross bar to form a V-shaped configuration therewith, all as shown.

I claim:

The ornamental design for a tricycle, as shown and described.
